UNITED STATES PATENT OFFICE.

JOHN T. WALSH, OF EAST ORANGE, NEW JERSEY, ASSIGNOR TO INDIAN REFINING COMPANY, OF NEW YORK, N. Y., A CORPORATION OF MAINE.

DESIGN FOR AN ADVERTISING DEVICE.

49,810.

Specification for Design.

Patented Oct. 24, 1916.

Application filed January 26, 1916. Serial No. 74,513. Term of patent 14 years.

To all whom it may concern:

Be it known that I, JOHN T. WALSH, a citizen of the United States, residing at East Orange, county of Essex, and State of New Jersey, have invented a new, original, and ornamental Design for Advertising Devices, of which the annexed is a specification, reference being had to the accompanying drawing and forming a part thereof.

The figure is a front view of an advertising device showing my new design.

I claim—

The ornamental design for an advertising device as shown.

JOHN T. WALSH.

Witnesses:

R. A. BARNETT,
D. G. SIEMER.
